FOLDING AUXILIARY TABLE
 James G. Hansen, Deerpath Road, Batavia, Ill.
 Filed Oct. 8, 1962, Ser. No. 228,805
 7 Claims. (Cl. 108—79)

The invention relates to an auxiliary table of the folding type and has reference in particular to such a table having two similar sections pivotally secured together and wherein each section provides a table of semi-circular area, triangular area or other geometrical shape.

An object of the invention resides in the provision of an auxiliary folding table which when completely erected will be round in area or two pivotally connected tables can be formed each semi-circular in area, and said auxiliary folding table when partially erected providing one table of semi-circular area.

A more specific object is to provide a folding type of table which may have a top surface of round area or which may be square or other geometrical shape and a table which when completely folded will provide a handle for carrying the folding table and which will be flat on both sides for convenient stacking.

A further object is to provide a folding table essentially consisting of two sections pivotally secured to each other and where in each section is in turn pivotally secured to a semi-circular table top along a flanged edge extending diametrically of the table top or if the top is triangular then the flanged edge will comprise the hypotenuse.

Another object of the invention is to provide a folding type of table wherein the supporting structure and table top includes two similar sections pivotally secured to each other and wherein each section comprises a two-legged unit having a third leg pivoted thereto.

With these and various other objects in view, the invention may consist of certain novel features of construction and operation, as will be more fully described and particularly pointed out in the specification, drawings and claims appended thereto.

In the drawings which illustrate an embodiment of the device and wherein like reference characters are used to designate like parts—

FIGURE 1 is a top plan view of the folding table of the invention showing the same completely erected to provide a round table area;

FIGURE 2 is a top plan view showing the folding table of FIGURE 1 in complete folded condition;

FIGURE 3 is an elevational view of the table as shown in FIGURE 1;

FIGURE 4 is an elevational view showing the table as it appears in the completely folded condition of FIGURE 2;

FIGURE 5 is a vertical sectional view taken substantially along line 5—5 of FIGURE 1;

FIGURE 6 is a vertical sectional view taken substantially along line 6—6 of FIGURE 1;

FIGURE 7 is a top plan view showing the table in erected condition so as to provide two tables of semi-circular shape;

FIGURE 8 is a perspective view of the pivoted sections of the table with the top removed;

FIGURE 9 is an enlarged detail sectional view on line 9—9 of FIGURE 1 showing the pivotal structure between a semi-circular top section and the particular unit supporting the same; and,

FIGURE 10 is a detailed sectional view showing a modified form of pivotal connection for the table sections. The supporting structure of the present folding table is best shown in FIGURES 4 and 8 wherein it will be observed that the units 10 and 12 are pivotally secured

2

to each other and wherein each unit has a pivotal connection with a third leg member 14 and 15. Each of the units 10 and 12 include a horizontal bar 16 and a pair of legs 17 and 18 for unit 10 and a horizontal bar 20 and the legs 21 and 22 for unit 12. The third leg member 14 consists of the horizontal bar 23 and leg 24 with the said bar 23 being pivotally connected at 25 to the horizontal bar 16 of unit 10. In a similar manner the third leg member 15 consists of a horizontal bar 26 and a leg 27, said bar 26 being pivotally secured at 28 to the horizontal bar 20 of unit 12. The legs 17 and 21 are pivotally connected to each other by hinges 30, FIGURES 3 and 4, and thus the units 10 and 12 can be spread apart or the units can be folded into contact with each other and secured in such folded relation by removable screws, mechanical fasteners, or other devices to hold the units 10 and 12 secured to one another.

The units 10 and 12 and the third leg members 14 and 15 may be formed of aluminum, steel or other suitable material and the material may be solid or tubular. As regards both the units and the third leg members, the same are so shaped as to provide the upstand portions 32, with each portion being integral with and forming an extension of its leg and the horizontal bars being also integral with or being suitably welded or mechanically fastened to their respective structure.

Referring to FIGURES 3 and 5 it will be clearly understood that the top sections of the table can be described as located within the confines of the portions 32. The said top sections 33 and 34 are shown as semi-circular but their specific shape is not limiting in any sense in that square, triangular, hexagonal or other shapes may be employed. Each top section includes the surfacing material 35 which may consist of a plastic, leather, cloth or other material suitable for a table top and which is backed by the layer of wood, metal, plastic, or any other suitable reinforcing material, such as 36. Here, also, for this table a plastic material or metal could be substituted for the wood. The peripheral edge of each semi-circular top section is provided with a depending flange 37 and the same may be reinforced and strengthened by reinforcing material of wood, metal, plastic or any other suitable material at position 40 or the depending flange may be non-existent, or may be an integral part of or non-separable from reinforcement 40.

The top section 33 is hinged to the horizontal bar 16 of the unit 10 and top section 34 is hinged in a similar manner to the horizontal bar 20 of the unit 12. For receiving the hinge structure, the diametrical edge of each semi-circular top section is provided with an angle member having a horizontal flange 41 and 42 for the sections 33 and 34 respectively, and a depending flange which is designated by the numerals 43 and 44, all as shown in FIGURE 5. The rivets 45 secure the horizontal flanges to their particular top section and each depending flange has a hinge such as 46 and 47 suitably secured thereto with the axis of the hinge coinciding with the bottom edge of the depending flange. For the top section 33 the hinge 46 is in turn fixed to the horizontal bar 16 and for the top section 34 the hinge 47 is secured to the horizontal bar 20. The diametrical edge of each top section overhangs its depending flange to an extent such as to provide a shallow recess for accommodating the handles 50 and 51. The said handles are thus completely enclosed when the top sections are horizontally disposed. However, the handles are conveniently accessible to the operator when the table is in a completely folded relation.

It is relatively easy to erect the folding table either to provide the full circular table of FIGURE 1 or the two half sections as shown in FIGURE 7. The third leg members 14 and 15 are revolved into a right angled

relation with their respective horizontal bar either 16 or 20, and the spring clips 52 which depend from each top section will engage the horizontal bar 23 or 26 to yielding hold the third leg members in extended relation. In addition to the full round table of FIGURE 1 and the two half sections of FIGURE 7, the auxiliary table of the invention can be partially erected to form a single half section. In such case the third leg member either 14 or 15 is released from its spring clip 52 and folded in against its particular horizontal bar to which it is pivotally secured. This will drop the semi-circular top section of the particular third leg member and the table is thus only half erected and half folded. When completed folded the handles 50 and 51 are exposed to facilitate the carrying of the folded table. It will also be observed that the table when completely folded is flat on both sides to enable a stacking of the tables on top of each other for shipment or for the other purposes.

The hinges 46 and 47 can be replaced by a hinge structure such as shown in FIGURE 10. A plate 54 is suitably secured to the undersurface of each table section by the rivets 55, and said plate provides a depending flange 56. A bracket 57 providing portions at right angles to each other is suitably fixed to each of the bars 16 and 20, and a pivot pin 58 connects each flange 56 to its bracket 57.

The invention is not to be limited to or by details of construction of the particular embodiment thereof illustrated by the drawings, as various other forms of the device, will be course be apparent to those skilled in the art without departing from the spirit of the invention or the scope of the claims.

What is claimed is:

1. In an auxiliary folding table, in combination, a pair of supporting units each consisting of a horizontal bar and a pair of legs connected by said bar to form a unitary structure, means pivotally connecting one leg of one unit to a leg of the other unit, whereby the units can be spread apart or folded against each other with respect to a vertical axis parallel to the pivotally connected legs, a third leg member pivoted to each unit, each third leg member including a horizontal bar having a leg at one end, the other end of the horizontal bar of each third leg member being pivoted to the horizontal bar of a unit approximately centrally of the unit, and a top for the table formed of two sections, one section being pivotally secured to the horizontal bar of one unit and the other top section being pivotally secured to the horizontal bar of the other unit.

2. In an auxiliary folding table, in combination, a pair of supporting units each consisting of a horizontal bar and a pair of legs connected by the bar to form a rigid unitary structure, hinge means pivotally connecting one leg of one unit to a leg of the other unit, whereby the units can be spread apart or closed against each other with respect to a vertical axis parallel to the pivotally connected legs, a third leg member pivoted to each unit, each third leg member including a horizontal bar having a leg at one end, the other end of the horizontal bar of each third leg member being pivotally connected to the horizontal bar of a unit approximately centrally of the unit and on the outer surface of its bar, and a top for the table formed of two sections, a depending flange on each top section extending along a diametrical chord of the section, hinge means pivotally connecting the flange of one section to the horizontal bar of one unit, and similar hinge means pivotally connecting the flange of the other section to the horizontal bar of the other unit.

3. An auxiliary folding table as defined by claim 2, wherein the hinge means pivotally connecting the depending flange of each section to the horizontal bar of its

respective unit is located along the bottom edge of its flange to connect the flange to the top surface of its bar.

4. An auxiliary folding table as defined by claim 3, additionally including a depending reinforcing flange extending around the peripheral edge of each top section.

5. An auxiliary folding table, including in combination, a pair of supporting units each consisting of a pair of spaced legs connected adjacent their top ends by a horizontal bar, hinge means pivotally joining a leg of one to a leg of the other unit, whereby the supporting units can be spread apart of folded against each other and with said movement taking place on a vertical axis parallel to the pivotally connected legs, a third leg member including a leg and a horizontal bar extending laterally therefrom, hinge means pivotally connecting the free end of the horizontal bar of each third leg member to the horizontal bar of a unit, whereby each third leg member can be extend laterally from its unit or can be folded in contact with its unit, and a top for the table, said top comprising two sections of approximately equal area, one section being pivotally secured to the horizontal bar of one unit and the other top section being pivotally secured to the horizontal bar of the other unit.

25 6. An auxiliary folding table as defined by claim 5, additionally including a flange member forming part of each top section along a diametrical chord, and the said top sections being pivotally secured to the horizontal bar of their unit by means of hinge members secured to the lower edge of the flange member of its respective top section and to the adjacent surface of its particular horizontal bar.

30 7. An auxiliary folding table, including in combination, a pair of supporting units each consisting of a pair of spaced legs integrally connected adjacent their top ends by a horizontal bar, hinge means pivotally joining a leg of one unit to a leg of the other unit whereby the supporting units can be spread apart or folded against each other, with said movement taking place on the vertical axis parallel to the pivotally connected legs, a third leg member including a leg and an integrally connected horizontal bar extending laterally therefrom, hinge means pivotally connecting the free end of the horizontal bar of a third leg member to the horizontal bar of a supporting unit, respectively, whereby each third leg member can extend laterally from its supporting unit or can be folded into contact with its unit, a top for the table, said top comprising two sections of approximately equal area, one section being pivotally secured to the horizontal bar of one unit and the other top section being pivotally secured to the horizontal bar of the other unit, a flange member forming part of each top section and being secured to the undersurface of each top section along a diametrical chord, hinge members pivotally securing each top section to the horizontal bar of its respective unit, said hinge members being secured to the lower edge of the flange member of its respective top section and to the adjacent surface of its particular horizontal bar, and a handle fixed to each horizontal bar approximately centrally of the bar and being disposed adjacent the outer surface of its particular flange member.
